UNITED STATES PATENT OFFICE.

FRANCISCO A. QUIROZ, OF MEXICO, MEXICO.

OIL-BURNER.

1,394,115.

Specification of Letters Patent.

Patented Oct. 18, 1921.

Application filed February 10, 1920. Serial No. 357,668.

To all whom it may concern:

Be it known that I, FRANCISCO A. QUIROZ, a citizen of the Republic of Mexico, and resident of the Federal District of the city of Mexico, Republic of Mexico, have invented certain new and useful Improvements in Oil-Burners, of which the following is a specification.

This invention relates to improvements in oil burners and more particularly to the type wherein crude oil is used as the fuel. Heretofore it has been the practice when utilizing such heavy oils for this purpose, to atomize the oil by utilizing a blast of air. Such structures require a large amount of mechanism for preparing the oil for fuel and as one of the principal objects of the present invention, I propose to change the mode of vaporizing the oil in order to avoid the use of any complicated mechanisms such as those above referred to.

Another object of the invention is to provide a crude oil burner wherein the oil is vaporized by the plunging of heated elements therein which when withdrawn create a mixture of air with the vaporized oil which is readily combustible and can easily be ignited.

Another important object of the invention is to provide a burner having a relatively few parts so that the same may be easily constructed and accessible should it be necessary to make repairs on the same.

With these and other objects in view this invention consists in the novel construction, combination and arrangement of parts which will be fully set forth in the following specification, claimed and illustrated in the accompanying drawings in which:—

Figure 1 is a side view of an oil burner and fuel tank constructed in accordance with this invention.

Fig. 2 is a top plan view of the oil burner of Fig. 1.

Fig. 3 is a transverse sectional view through the device.

Fig. 4 is a side view of the modified form of the invention.

Fig. 5 is a plan view of Fig. 4, and

Fig. 6 is a transverse sectional view through Fig. 5.

Referring to the drawings in detail the numeral 10 designates a suitable reservoir for containing a fuel which is led to a valved pipe 11 to the burner designated generically by the numeral 12.

The burner 12 above referred to consists of a main trough 13 having its bottom curved downwardly to form a longitudinally extending pocket 14. This trough is closed by end walls 15 having recesses 16 therein for the reception of the ends of a shaft 17 upon which the burner disks are mounted.

Formed on the rear walls 18 of the trough 13 intermediate its ends, is a chamber 19 which is provided with an inlet opening 20 through which the feed pipe 11 is connected. An outlet passage or opening 21 is formed in the wall 18 and establishes communication between the chamber 19 and the trough 13 so that the oil admitted to the chamber may enter the trough and fall by gravity into the longitudinal depression or recess 14.

A spreader 22 is secured to the rear wall 18 and extends downwardly from a point slightly above the opening 21 to a point in a plane with the rear edge of the recess 14. The ends of the spreader flare outwardly as illustrated in Fig. 2, and the extreme forward edge 23 of said spreader is spaced slightly above the bottom wall 24 of the trough 13. It will thus be seen that the oil flowing into the chamber 19 and out through the passage 21 will be spread outwardly so that only a thin film is admitted to the recess 14 thereby preventing flooding the burner or in any way concentrating too great a quantity of oil at any one point.

Mounted at spaced intervals on the shaft 17 are disks 25 which are held in spaced relation by suitable spacers 26. These disks while through experiment have operated successfully with perfectly smooth surfaces, may should it be found desirable, be perforated or otherwise roughened as at 27 to cause the oil to adhere thereto during the operation of the device. In order to rotate the disks there is provided a suitable operating mechanism such as is illustrated at 28 in Fig. 2, and it will be obvious that upon setting the device in motion the entire periphery of each disk will be brought into contact with the oil in the trough.

As the disk is rotated it will be obvious that the oil will adhere in a thin film to each disk and upon mixing with the atmosphere will create a combustible mixture which may be readily ignited. As combustion takes place and the burner becomes heated, it will be obvious that the disks will become extremely hot and when their heated edges contact with the oil obviously the oil imme-

diate contact therewith will become vaporized and may be easily mixed with the oxygen.

In order to prevent too thick a coating of oil upon the disks there is provided a wiper 5 designated generically by the numeral 29 which consists of a back 30 provided with a securing flange 31 at one edge and at its opposite edge with a plurality of fingers 32 which project upwardly and inwardly from 10 the forward edge of the trough 13 toward the center of the shaft 17. It will therefore be seen that any excessive accumulation of oil upon the disks will be wiped from their surfaces before the same pass around into 15 position where the oil bursts into flame. And the excess oil will be confined within the trough and thereby prevent it from interfering in any way with the proper operation of the device.

20 In the construction of the device illustrated in Fig. 4 to Fig. 6 inclusive, a trough is designated by the numeral 33 and the end walls 34 thereof are provided with recesses 35 in which the shafts 36 are journaled.

25 Each of these shafts is provided with a gear 37 which gears are in mesh as illustrated in Figs. 4 and 5 and it will therefore be obvious that upon turning one of the shafts 36 the other will rotate in the opposite direction. In order to drive the device 30 when thus constructed, a suitable operating means such as a motor 38 may be provided and connected with one of the shafts in any preferred manner.

35 Mounted on each shaft is a plurality of spaced disks 39 which are held in spaced relation by suitable spacers 40 and as illustrated in the drawings, these disks intermesh. It will thus be seen that a concentrated flame from the burner when constructed in this manner is obtained without materially complicating the structure. When the burner is constructed in this manner there are provided the wipers 41 which 40 prevents the accumulation of excess oil upon 45 the disks. The remaining structure is practically as that previously described, except in that the trough or pocket referred to by

the character 14 in Fig. 3, is widened slightly in order to accommodate both disks.

50 While in the foregoing there has been shown and described the preferred embodiment of this invention it is to be understood that certain minor changes in the details of construction, combination and arrangement 55 of parts may be resorted to without departing from the spirit and scope of the invention as claimed.

What is claimed is:—

1. An oil burner comprising a trough for 60 containing fuel oil, disks rotatably mounted upon the trough, portions of their peripheries immersed in the fuel oil and means for rotating the disks.

2. An oil burner comprising a trough for 65 containing fuel oil, rotatably mounted disks associated with the trough whereby their peripheries are immersed in the fuel oil and means to rotate the disks.

3. An oil burner comprising a trough for 70 containing fuel oil, rotatably mounted disks associated with the trough having their peripheries immersed in the fuel oil, means to prevent flooding of the trough and means to rotate the disks.

75 4. An oil burner comprising a trough for containing fuel oil, rotatably mounted disks associated with the trough having their peripheries immersed in the fuel oil, means for rotating the disks and wipers for preventing 80 the accumulation of an excessive amount of oil on the disks.

5. An oil burner comprising a trough for containing fuel oil, a plurality of rotatable disks associated with the trough, said trough 85 having a chamber communicating therewith for conducting the fuel oil there into, a spreader within the trough for preventing the flooding of the trough with fuel oil and wipers between the disks to avoid the accumulation of an excessive amount of fuel oil on the disks, and means to rotate said disks.

Signed in the city, county and State of New York.

FRANCISCO A. QUIROZ.
